ELECTRIC CONDENSER

Application filed September 20, 1929, Serial No. 394,041, and in Switzerland October 5, 1928.

This invention relates to electric condensers of the type in which the condenser units are composed of superposed sheets of conducting and insulating material spirally wound into a 5 cylindrical form. These units are in the case of condensers of large capacity usually immersed in a liquid dielectric such as oil, so that any heat generated during operation is dissipated. There is however a possibility 10 after a time of water in the form of moisture entering the liquid dielectric, in which the condenser units are constantly immersed and if this moisture can penetrate into the condenser units, the effect is very serious owing 15 to the increase in the losses and the inevitable ultimate puncture or breakdown of the insulation.

In condensers comprising wound condenser units the latter are as a rule arranged in a 20 vertical position that is to say, their flat end surfaces are horizontal and any moisture slowly entering the oil falls directly on to the flat surfaces of the units, and is caught there, gradually penetrating into the interior 25 of the units and eventually causing their breakdown.

The object of the present invention is to overcome these disadvantages and for this purpose, according to the invention, the 30 wound condenser units instead of being spaced apart in an upright position in the liquid dielectric, are horizontally arranged in such a manner that moisture penetrating into the dielectric will fall on to the peripheral surfaces of the condenser units and sink to the bottom. It should be observed that 35 although the horizontal or vertical position of the condenser elements is immaterial as regards the disadvantageous action above explained in the case of paraffin-insulated condensers, the replacement of a damaged condenser unit is, in such condensers, very difficult or even impossible.

40 The accompanying drawing shows by way of example, one constructional form embodying the invention:

Figure 1 is a perspective view of the apparatus, the condenser itself being raised out of 45 a tank containing the oil bath;

Figure 2 shows one unit of the apparatus on a larger scale;

Figure 3 illustrates the electrical connections of the condenser units in a delta connection.

55

The condenser units *a*, which are constructed in a known manner by winding on a hollow core metal sheets with interleaved strips of paper soaked in oil, are arranged in a horizontal position and are supported by the 60 cover *b*, composed of insulated material, of a tank *c* containing the oil bath. The units are arranged in groups between two vertical metal supporting rods *d*, on which they are mounted by means of the projecting end 65 sleeves *e* of their hollow cores, the spacing apart of the several units on the rods *d* being ensured by suitable distance sleeves *g*.

The rods *d* not only serve for the support of the condenser units but also for the electrical 70 connection to the condenser terminal strips or lugs *h*, provided on the ends of the condenser units. The rods *d* are connected on the under side of the cover *b* to the terminals *i* in a delta connection by means of wires as 75 shown in Figure 3. The removable cover *b* from which the rods *d* are suspended allows the condenser units to be withdrawn as a whole from the liquid dielectric bath.

In the horizontal position of the condenser 80 units *a* above described any moisture penetrating into the oil bath drips down on the peripheral surface of the units and sinks to the bottom of the tank, which can be provided with a collecting and draining chamber for 85 drawing off the water. In any case, the water cannot penetrate into the inside of the condenser units since even if water should collect on to the outer metal sheet of the unit it cannot penetrate further, but is detained 90 at this surface and water evidently cannot enter the vertical front surfaces of the condenser units. In this connection it should be observed that in the improved construction 95 of condenser the metal sheets only are arranged to project on both flat surfaces of the units, the paper insulation which might absorb moisture being set back at each layer within the projecting edges of the metal sheets. As the heating of the units relative 100

to the temperature of the oil bath is only slightly higher (possibly 2-3° C.), the oil which is trapped in the unit remains stationary, and no circulation of oil occurs through the unit itself.

5 Furthermore at the flat surfaces of the condenser units, the oil is retained by adhesion on the metal sheets so that it is therefore quite impossible for moisture when present in the dielectric to penetrate into the condenser unit and cause its breakdown.

10 The mounting of the condenser units in the oil bath cover is of course, only referred to by way of example, and the connections of 15 the multiple unit condenser could also be effected in the oil bath container by means of the supporting and current conducting rods. The number of condenser units employed is also not limited although the construction described is particularly adapted 20 for condensers of small capacity.

What I claim is:—

1. An electric condenser comprising a tank 25 with a liquid dielectric therein and a plurality of wound condenser units of the kind described, the latter being arranged spaced apart from one another within the liquid dielectric in a horizontal position in such a manner that moisture penetrating into the dielectric will fall on to the peripheral surfaces 30 of the condenser units and sink down to the bottom of the tank, for the purpose specified.

2. An electric condenser comprising a tank 35 with a liquid dielectric therein and a plurality of wound condenser units of the kind described, the latter being arranged spaced apart from one another within the liquid dielectric in a horizontal position, and vertical rods for supporting the condenser units, said 40 rods serving also for electric connection of the condenser units and carrying distance sleeves to maintain the condenser units spaced apart on the rods, for the purpose specified.

3. An electric condenser comprising a tank 45 with a liquid dielectric therein and a plurality of wound condenser units of the kind described, the latter being arranged spaced apart from one another within the liquid dielectric in a horizontal position, vertical rods 50 for supporting the condenser units, said rods serving also for electric connection of the condenser units and carrying distance sleeves to maintain the condenser units spaced apart on the rods, and a movable carrying element 55 by which said rods are carried in suspended position and which allows the condenser units to be withdrawn as a whole from the liquid dielectric.

60 In witness whereof I have hereunto signed my name this 9th day of September 1929.
EMIL HAEFELY.
